DESIGN FOR A KNIFE FOR USE IN RETRIEVING FISHING FLIES

Eldridge A. Douglass, San Francisco, Calif.

Application May 16, 1938, Serial No. 77,221

Term of patent 7 years

To all whom it may concern:

Be it known that I, Eldridge A. Douglass, a citizen of the United States, residing at the city and county of San Francisco, State of California, have invented a new, original, and ornamental Design for a Knife for Use in Retrieving Fishing Flies, of which the following is a specification, reference being had to the accompanying drawing, forming part thereof.

Figure 1 is a view in side elevation of a knife, showing my new design.

Figure 2 is a view in end elevation, the direction of view being indicated by the arrow 2 of Figure 1.

I claim:

The ornamental design for a knife for use in retrieving fishing flies, substantially as shown.
